WILLIAM W. PRICE, OF POUGHKEEPSIE, NEW YORK, ASSIGNOR TO DE LAVAL SEPARATOR COMPANY, A CORPORATION OF NEW JERSEY.

CREAM-REGULATING DEVICE FOR SEPARATORS.

SPECIFICATION forming part of Letters Patent No. 733,273, dated July 7, 1903.

Application filed April 14, 1903. Serial No. 152,503. (No model.)

To all whom it may concern:

Be it known that I, WILLIAM W. PRICE, a citizen of the United States, residing at Poughkeepsie, county of Dutchess, and State of New York, have invented a new and useful Improvement in Cream-Regulating Devices for Separators, of which the following is a full, clear, and exact description, reference being had to the accompanying drawings, which 10 form a part of this specification.

The object of my invention is to regulate and vary during the revolution of the bowl the density of the cream discharge. I accomplish this object by the mechanism herein- 15 after described.

In the drawings, Figure 1 is a side elevation of my separator with a portion of the cover broken away, showing the ring in section and the adjusting-screw. Fig. 2 is an enlarged 20 section on line 2 2, Fig. 1. Fig. 3 is an enlarged inside view of the ring and wings. Fig. 4 is a section on line 4 4, Fig. 3. Figs. 5 and 6 are perspective views of the wings. Fig. 7 is an enlarged section of rollers and 25 end of adjusting-rod.

A is the case of a centrifugal separator; B, the bowl; b, the neck of the bowl; C, the feed-cup.

D is the skim-milk outlet, and E the cream- 30 outlet.

Surrounding the neck of the bowl so as to make a sliding fit is the ring F, having the flange f. This ring F is placed upon the neck of the bowl in such position that the flange f 35 is above the top of the neck of the bowl. In the side of the ring F is the elongated orifice or slot f'. Projecting outward through this orifice is the tube f², having secured to it at a point on the inner side of the ring a wing G, 40 having angular faces g g'. The wall of the inner end of the tube f² is cut away, forming orifice g², the inner end of which is flared outwardly by inclined ends g³. Surrounding this tube f² within the ring is a tube f³, hav-

ing raised above its outer end a wing G', corresponding to, but projecting in opposite directions from, the wing G. The inner end of the tube f³ is cut away to correspond with the inner end of tube f², forming an orifice g⁴ 45 with inclined ends g⁵. In one position, as hereinafter described, the orifices g² and g⁴

and the inclined ends g³ and g⁵ coincide. The tubes f² and f³ are slidably fitted one upon the other. As may be seen, by sliding one tube upon the other through the medium of 55 the wings the orifices g² and g⁴ may be brought from a position of coincidence to positions where the orifice in the tube f³ is more or less cut off. The wings G' and G are in alinement with and on the same level with 60 each other, and thus the limit of motion is obtained by the inner ends striking in the movement in either direction. This is so adjusted that it occurs before there has been sufficient movement to cause the inclined ends g³ to 65 pass beyond the inclined ends g⁵, and thus entirely inclose the orifices g² and g⁴. The orificed ends g² and g⁴ of the tubes f² and f³ are inserted within the bowl through the cream-outlet E in the bowl. As may be 70 seen, by moving the wings G G', so as to more or less close the orifices g² and g⁴, the density of the cream delivered from the bowl will be varied. I accomplish this movement of the wings while the bowl is rotating 75 in the following manner: The outer end of the tube f² extends outwardly through the orifice or slot f', as hereinbefore described. The inner surface of the ring is cut away at H H' to form seats for the wings G G', respectively, the cut-away portions being bound by upper and lower concentric curved portions h and h', the width of the cut-away portions being equal to the width of the wings G G'. The tubes and wings are placed in position so that the orificed portions g² and g⁴ 80 are on the lower surfaces of the tubes. As may be seen, the vertical positions of the tubes f² and f³ are fixed. It may also be seen that by moving the ring upwardly the orifices g² and g⁴ are enlarged. By moving the ring downwardly the orifices g² and g⁴ are contracted. I move this ring up and down, when 85 the bowl is rotated by the following mechanism:

I is a rod having at its lower end the projecting rollers i' i², the space between which is slightly greater than the thickness of the flange f of the ring F. The upper portion of this rod has the thread i³ cut thereon and the 90 internally-threaded nut i⁴. Above and below this nut i⁴ and surrounding the rod are

the bearings J, secured to the feed-cup D. Any other non-rotatable portion of the machine will answer as well as the feed-cup D to which to secure the bearings D. Near the 5 upper end of the rod I is the projecting rod K. The position of the parts as shown is such that by moving the rod K the rollers i and i^2 will be brought respectively above and below the flange f. When in this position, 10 by turning the nut i^4 in one direction the rod I is elevated, and through the medium of the roller i^2 the ring F is elevated and the density of the cream decreased, and when the nut is turned in the other direction through 15 the medium of roller i the ring F is depressed and the density of the cream increased. As the ring F is rotating with the bowl and thus rapidly, the action of rollers i or i^2 is practically upon the whole circumference of the 20 flange f of ring F.

Having now fully described my invention, what I claim, and desire to protect by Letters Patent, is—

1. In a centrifugal cream - separator, in 25 combination, with the bowl, provided with a cream-outlet orifice, of tubes, slidably fitted one upon the other, projecting within the bowl through said cream-outlet orifice, each of said tubes having an elongated cut-away portion 30 at its inner end, said tubes being adapted to revolve upon each other to bring said cut-away portions in variable coincidence with each other.

2. In a centrifugal cream - separator, in 35 combination, with the bowl, provided with a cream-outlet orifice, of tubes, slidably fitted one upon the other, projecting within the bowl through said cream-outlet orifice, each of said tubes having an elongated cut-away portion 40 at its inner end, said tubes being adapted to revolve upon each other to bring said cut-away portions in variable coincidence with each other, and a stop for limiting the movement of said tubes upon each other.

45 3. In a centrifugal cream - separator, in combination, with the bowl, provided with a cream-outlet orifice, of tubes slidably fitted one upon the other projecting within the bowl through said cream-outlet orifice, each of said 50 tubes having an elongated cut-away portion at its inner end, said tubes being adapted to revolve upon each other to bring said cut-away portions in variable coincidence with each other, the inner end of said cut-away portions being correspondingly flared.

55 4. In a centrifugal cream - separator, in combination, with the bowl, provided with a cream-outlet orifice, of tubes, slidably fitted one upon the other, projecting within the bowl 60 through said cream-outlet orifice, each of said tubes having an elongated cut-away portion at its inner end, said tubes being adapted to revolve upon each other to bring said cut-away portions in variable coincidence with 65 each other, the inner end of said cut-away portions being correspondingly flared, and a stop

for limiting the movement of said tubes upon each other.

5. In a centrifugal cream - separator, in combination, with the bowl, provided with a 70 cream-outlet orifice, of tubes, slidably fitted one upon the other, projecting within the bowl through said cream-outlet orifice, each of said tubes having an elongated cut-away portion at its inner end, said tubes being adapted to 75 revolve upon each other to bring said cut-away portions in variable coincidence with each other, and means adapted, during the revolution of said bowl, to revolve said tubes upon each other. 80

6. In a centrifugal cream - separator, in combination, with the bowl, provided with a cream-outlet orifice, of tubes, slidably fitted one upon the other, projecting within the bowl through said cream-outlet orifice, each of said 85 tubes having an elongated cut-away portion at its inner end, said tubes being adapted to revolve upon each other to bring said cut-away portions in variable coincidence with each other, and a stop for limiting the move- 90 ment of said tubes upon each other, and means adapted, during the revolution of said bowl, to revolve said tubes upon each other.

7. In a centrifugal cream - separator, in combination, with the bowl, provided with a 95 cream-outlet orifice, of tubes, slidably fitted one upon the other, projecting within the bowl through said cream-outlet orifice, each of said tubes having an elongated cut-away portion 100 at its inner end, said tubes being adapted to revolve upon each other to bring said cut-away portions in variable coincidence with each other, the inner end of said cut-away portions being correspondingly flared, and means adapted, during the revolution of said bowl, 105 to revolve said tubes upon each other.

8. In a centrifugal cream - separator, in combination, with the bowl, provided with a cream-outlet orifice, of tubes, slidably fitted one upon the other, projecting within the bowl 110 through said cream-outlet orifice, each of said tubes having an elongated cut-away portion at its inner end, said tubes being adapted to revolve upon each other to bring said cut-away portions in variable coincidence with 115 each other, the inner end of said cut-away portions being correspondingly flared, and a stop for limiting the movement of said tubes upon each other, and means adapted, during the revolution of said bowl, to revolve said tubes 120 upon each other.

9. In a centrifugal cream - separator, in combination, with the bowl provided with a cream-outlet orifice and a device in said outlet adapted in its movement to vary the density 125 of the cream-discharge, of a ring slidably fitted upon the neck of the bowl, connection between said ring and said cream-density device adapted in the vertical movement of the ring to operate said cream-density device and a non- 130 rotatable device adapted to elevate and depress said ring.

10. In a centrifugal cream - separator, in combination, with the bowl provided with a cream-outlet orifice and a device in said outlet adapted in its movement to vary the density of the cream-discharge, of a ring slidably fitted upon the neck of the bowl, connection between said ring and said cream-density device adapted in the vertical movement of the ring to operate said cream-density device, said ring having a flange, a rod, projections from said rod adapted to rest respectively above and below said flange, said rod being supported so as not to rotate and means to elevate and depress said rod.
11. In a centrifugal cream - separator, in combination, with the bowl, provided with a cream-outlet orifice and a device in said outlet adapted in its movement, to vary the density of the cream discharged, of a ring slidably fitted upon the neck of the bowl, connection between said ring and said cream-density device adapted in the vertical movement of the ring to operate said cream-density device, said ring having a flange, a rod, projections from said rod adapted to rest respectively above and below said flange, said rod having a threaded portion, a nut upon said threaded portion and fixed bearings above and below said nut.
12. In a centrifugal cream - separator, in combination, with the bowl provided with a cream-outlet orifice and a device in said outlet adapted in its movement to vary the density of the cream discharged, of a ring slidably fitted upon the neck of the bowl, connection between said ring and said cream-density device adapted in the vertical movement of the ring to operate said cream-density device, said ring having a flange, a rod, projections from said rod adapted to rest respectively above and below said flange, a rod projecting from the upper end of said first-mentioned rod whereby said first-mentioned rod may be turned so that the projections may be brought into and out of alinement with said ring - flange, said first-mentioned rod being supported so as not to rotate and means to elevate and depress said rod.
13. In a centrifugal cream - separator, in combination, with the bowl provided with a cream-outlet orifice and a device in said outlet adapted in its movement to vary the density of the cream discharged, of a ring slidably fitted upon the neck of the bowl, connection between said ring and said cream-density device adapted in the vertical movement of the ring to operate said cream-density device, said ring having a flange, a rod, projections from said rod adapted to rest respectively above and below said flange, a rod projecting from the upper end of said first-mentioned rod whereby said first-mentioned rod may be turned so that the projections may be brought into and out of alinement with said ring-flange, said first-mentioned rod having a threaded portion, a nut upon said threaded portion and fixed bearings above and below said nut.
14. In a centrifugal cream - separator, in combination, with the bowl provided with a cream-outlet orifice, of tubes slidably fitted one upon the other projecting within the bowl through said cream-outlet orifice, each of said tubes having an elongated cut-away portion at its inner end, said tubes being adapted to revolve upon each other to bring said cut-away portions in variable coincidence with each other, inclined projecting wings upon each of said tubes, a ring slidably fitted upon the neck of the bowl, there being cut-away portions upon the inner surface of said ring, of width substantially equal to that of the greatest width of wings, in which said wings rest, there being an elongated slot through said ring and a device supported so as not to rotate with the bowl adapted to elevate and depress said ring.
15. In a centrifugal cream - separator, in combination, with the bowl provided with a cream-outlet orifice, of tubes slidably fitted one upon the other projecting within the bowl through said cream-outlet orifice, each of said tubes having an elongated cut-away portion at its inner end, said tubes being adapted to revolve upon each other to bring said cut-away portions in variable coincidence with each other, inclined projecting wings upon each of said tubes, a ring slidably fitted upon the neck of the bowl, there being cut-away portions upon the inner surface of said ring, of width substantially equal to that of the greatest width of wings, in which said wings rest, there being an elongated slot through said ring and a device supported so as not to rotate with the bowl adapted to elevate and depress said ring.
16. In a centrifugal cream - separator, in combination, with the bowl provided with a cream-outlet orifice, of tubes, slidably fitted one upon the other, projecting within the bowl through said cream-outlet orifice, each of said tubes having an elongated cut-away portion at its inner end, said tubes being adapted to revolve upon each other to bring said cut-away portions in variable coincidence with each other, inclined or angular projecting wings upon each of said tubes, a ring slidably fitted upon the neck of the bowl, there being cut-away portions upon the inner surface of said ring, of width substantially equal to that of the greatest width of wings, in which said wings rest, there being an elongated slot through said ring, said ring having a flange, a rod, projections from said rod adapted to rest respectively above and below said flange, said rod being supported so as not to rotate with the bowl and means to elevate and depress said rod.
17. In a centrifugal cream - separator, in

combination with the bowl provided with a cream-outlet orifice, of tubes slidably fitted one upon the other projecting within the bowl through said cream-outlet orifice, each of said 5 tubes having elongated cut-away portions at its inner end, said tubes being adapted to revolve upon each other to bring said cut-away portions in variable coincidence with each other, inclined or angular projecting 10 wings upon each of said tubes, a ring slidably fitted upon the neck of the bowl, there being cut-away portions upon the inner surface of said ring, of width substantially equal to that of the greatest width of wings, in 15 which said wings rest, there being an elongated slot through said ring, said ring having a flange, a rod, projections from said rod adapted to rest respectively above and below said flange, a rod projecting from the upper end of said first-mentioned rod whereby said first-mentioned rod may be turned so 20 that the projections may be brought into and out of alinement with said ring-flange, said first-mentioned rod being supported so as not to rotate with the bowl and means to elevate 25 and depress said rod.

18. In a centrifugal cream-separator, in combination with the bowl provided with a cream-outlet orifice, of tubes slidably fitted 30 one upon the other projecting within the bowl

through said cream-outlet orifice, each of said tubes having elongated cut-away portions at its inner end, said tubes being adapted to revolve upon each other to bring said cut-away portions in variable coincidence with each 35 other, inclined projecting wings upon each of said tubes, a ring slidably fitted upon the neck of the bowl, there being cut-away portions upon the inner surface of said ring, of width substantially equal to that of the greatest 40 width of wings, in which said wings rest, there being an elongated slot through said ring, said ring having a flange, a rod, projections from said rod adapted to rest respectively above and below said flange, a rod projecting from the upper end of said first-mentioned rod whereby said rod may be turned so that the projections may be brought into and out of alinement with said ring-flange, said first-mentioned rod having a threaded 45 portion, a nut upon said threaded portion and fixed bearings above and below said nut.

In testimony of which invention I have hereunto set my hand, at Philadelphia, on this 9th day of April, 1903.

WILLIAM W. PRICE.
